UNITED STATES PATENT OFFICE.

WILLIAM D. LEFTWICH, OF PITTSBURG, PENNSYLVANIA.

COUPLING MECHANISM.

No. 900,558.

Specification of Letters Patent.

Patented Oct. 6, 1908.

Application filed April 3, 1907. Serial No. 366,180.

To all whom it may concern:

Be it known that I, WILLIAM D. LEFTWICH, a citizen of the United States, residing at Pittsburgh, in the county of Allegheny and 5 State of Pennsylvania, have invented certain new and useful Improvements in Coupling Mechanism, of which the following is a specification, reference being had therein to the accompanying drawing.

- 10 My invention refers to improvements in couplings and is designed for the purpose of providing a car coupler with supplemental coupling mechanism for the hose terminals of the air supply or steam supply of the brake 15 or heating system of a train, so constructed as to accomplish automatic coupling and uncoupling of the hose terminals, simultaneously with the coupling and uncoupling of the cars.
- 20 The invention is shown in the accompanying drawings, in which

Figure 1. is a plan view of the apparatus showing the coupling jaws and hose terminals connected for operation. Fig. 2. is a 25 similar view showing the parts separated and about to be coupled together. Fig. 3 is a side elevation of Fig. 1. Fig. 4. is a vertical sectional view on the line IV. IV. of Fig. 1. Fig. 5. is a cross sectional view on the line V. V. of 30 Fig. 3.

In the drawings, 2, 2, represent the coupling jaws of a standard coupler of the Janney type, of well known construction provided with pivoted jaws 3, 3, for automatic interlocking engagement, each of said jaws being provided with the inner arm 4 adapted in the locked position to be engaged and held by the inner end 5 of lever 6. Said lever extends transversely of each coupling head 2 and is pivotally mounted at 7, having a terminal 8 extending outwardly at one side and adapted to be raised by any suitable connection 9 against the pressure of spring 10. Said spring is interposed between the outer end of 40 lever 6 and any suitable supporting abutment 11, by which arrangement the locking terminal 5 of arm 6 will automatically engage in front of the inner end of arm 4 to hold the coupling jaw in locking position after the 45 couplers have been brought together, as will be readily understood.

12, 13, represent the terminal ends of the hose of an air brake or steam system, one of said hose terminals 12 being connected with 55 an abutting terminal 14, the other hose 13 being connected with a similar abutting ter-

75 minal 15 respectively, mounted on each of the coupling heads in such a position as to be brought into abutting contact when the coupling heads are together, as shown in Fig. 60 4. Terminals 14 and 15 are hollow as shown at a and b respectively, Fig. 4.

Each coupling head 2 is provided at one side with the coupling abutment 14 and the coupling abutment 15 at the other side, so 65 arranged that when the car couplers are connected, the fluid coupling abutments will make contact at each side, as shown in Fig. 1. For the purpose of insuring tight communicating contact one or the other of said abutments, as abutment 14, is provided with a packing gasket 16 of rubber or other suitable resilient material, whereby a tight joint is secured.

70 Abutments 14 are preferably rigidly attached to or made integral with the coupling head 2 as shown, and are preferably provided with forwardly extending horns 17 arranged to insure the centralization and proper contact of the companion abutment 15, while below the circulation abutment 14 is the guiding socket 18 having an inwardly tapering cavity 18' for the purpose of centralizing and guiding said companion abutment to position. For such purpose abutment 15 is provided with a forwardly projecting tapered horn 19 arranged to enter the cavity 18' in the operation of coupling 75 and to guide the abutment into suitable contacting position, abutment 15 and horn 19 90 being preferably in one piece. For the purpose of supporting said parts, I provide a housing 20 mounted on the side or integral with the coupling head 2, in which is mounted a stem 21 and an interposed spring 22 surrounding a reduced extension 23 of said stem and adapted to project it outwardly in advance of the housing. Between stem 21 and abutment 15 and its horn 19, is interposed one or more coupling links 24 pivotally connected with the abutment and stem 95 respectively by pins 25 and 26 as shown. By this construction I provide a universally flexible joint so that either lateral or vertical deflection of the abutment with relation to its carrying stem is provided, thereby 100 overcoming and compensating for variation in the car or other variation due to movement of travel, inequalities in the roadbed, etc.

105 At its rear end stem 23 is provided with a guiding pin 27 arranged to enter a guiding

slot 28 in the upper portion of housing 20 and to maintain the stem 21 in proper position for holding the abutment upright above horn 19, while a terminal collar 29, is mounted at the end of stem 23 to limit its forward movement. Each abutment 15 as thus constructed and mounted is capable of an independent longitudinal movement with relation to its supporting coupling head 2 and for the purpose of locking said abutment 15 against the relatively immovable coupling abutment 14, I provide wedges 30, 30, forming elements of a sliding bolt 31, mounted for lateral adjustment transversely across the top of each coupling head 2, as clearly shown in Figs. 1 and 2. Each of said bolts 31 is provided with upper and lower guiding stems 32, 32' adapted to slide in receiving slots or openings 33, 33', above and below the central opening a therethrough. At the other end the bolt 31 is provided with a terminal 34 mounted in a bearing 35 and at the front is provided with a forwardly projecting lug 31' by which it is actuated.

25 36 is an actuating arm mounted on the upper end of the pivotal stem 37 of each coupler and adapted to swing with the coupling jaw thereof and provided with a terminal so arranged as to embrace and engage the lug 31' of bolt 31. Thus when the coupling jaws 3 are swung inwardly in the operation of making the car coupling, terminal 36 engaging lug 31' will thrust the wedges 30 inwardly engaging corresponding tapered sockets 38, 38, in the upper or upper and lower sides of coupling abutments 15, thereby closely binding the abutting terminals of such air coupling devices in close contact with each other, as shown in Fig. 1. On 40 the other hand, when the ordinary couplers are uncoupled and the jaws 3 are swung outwardly, then the shorter terminals 39 of swinging jaws 36 engage behind lugs 31' of jaws 31, throwing them back in the opposite direction, relieving the binding connection of abutments 14 and 15, and allowing them to be opened and drawn apart.

The operation of the invention will be readily understood from the foregoing description.

50 The guiding horns 19 entering their appropriate sockets 18' will centralize the hose

terminal abutments so that they will be brought into intimate contact and then locked together, while the mounting of the 55 parts provides for sufficient flexibility to compensate for any of the variations arising in service.

The invention may be variously changed or modified in construction, design, or other 60 details by the skilled mechanic, but all such changes are to be considered as within the scope of the following claims.

What I claim is:

1. In a car coupler, the combination with 65 the main coupler head provided with a swinging jaw and a fluid conducting terminal at one side adapted to receive and make connection with a co-acting terminal of another similar coupler; of a transversely arranged 70 sliding locking wedge adapted to tighten said terminals together, with an actuating arm operable by the swinging jaw and adapted to move said wedge in conformity with the movement of the jaw, substantially as set 75 forth.

2. In a car coupler, the combination of a main coupler head provided with a swinging jaw, a fluid-conducting terminal at one side thereof adapted to receive and make connection with a co-acting terminal of another similar coupler and having a vertically arranged portion provided with a tapered guiding socket, a fluid-conducting terminal at the other side of the coupler head provided with 85 a vertically arranged guiding projection and a guide stem loosely coupled therewith, a guiding housing mounted on the coupler head engaging said stem and provided with a cushioning spring, a transversely arranged 90 sliding locking wedge adapted to engage and couple together one of said conducting terminals with the terminal of a co-acting coupler head, and an actuating arm operable by the swinging jaw of the coupler adapted to 95 move said wedge in conformity with the movement of the jaw, substantially as set forth.

In testimony whereof I affix my signature in presence of two witnesses.

WILLIAM D. LEFTWICH.
